(57) **CLAIM**

The ornamental design for a scouring pad clamp with scraper for grill cleaning, as shown.

DESCRIPTION

FIG. 1 is an isometric view of a scouring pad clamp with scraper for grill cleaning showing my new design;

FIG. 2 is a top plan view thereof;

FIG. 3 is a bottom plan view thereof;

FIG. 4 is a side elevational view thereof shown in an alternate position of use, the opposite side elevational view being a mirror image thereof;

FIG. 5 is an enlarged front end view of FIG. 4; and,

FIG. 6 is a rear end view thereof.
